US00D817252S

(12) **United States Design Patent** (10) **Patent No.:** **US D817,252 S**
(45) **Date of Patent:** **** May 8, 2018**

(54) **DRONE**

(71) Applicant: **Samsung Electronics Co., Ltd.**, Suwon-si (KR)

(72) Inventors: **Eunyoung Kim**, Seongnam-si (KR); **Hayoul Jung**, Yongin-si (KR); **Sangil Park**, Seoul (KR)

(73) Assignee: **SAMSUNG ELECTRONICS CO., LTD.**, Suwon-si (KR)

(**) Term: **15 Years**

(21) Appl. No.: **29/581,365**

(22) Filed: **Oct. 18, 2016**

(30) **Foreign Application Priority Data**

Apr. 19, 2016 (KR) 30-2016-0018733

(51) **LOC (11) Cl.** **12-07**

(52) **U.S. Cl.**

USPC **D12/325**; D12/16.1

(58) **Field of Classification Search**

USPC D12/3, 16.1, 319-345; D21/436-455

CPC B64C 39/024; B64C 2201/108

See application file for complete search history.

(57) **CLAIM**

The ornamental design for a drone, as shown and described.

DESCRIPTION

FIG. 1 is a top perspective view of a drone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

The dashed broken lines in the drawings represent portions of the drone that form no part of the claimed design.

1 Claim, 8 Drawing Sheets
